(57) **CLAIM**

The ornamental design for a connector for backlight, as shown and described.

DESCRIPTION

FIG. 1 is a front elevational view of a connector for backlight showing my new design;

FIG. 2 is a top plan view thereof;

FIG. 3 is a right side elevational view thereof; and

FIG. 4 is a left side elevational view thereof; and

FIG. 5 is a rear elevational view thereof;

FIG. 6 is a bottom plan view thereof.

FIG. 7 is a top, front, and left perspective view thereof.

FIG. 8 is a top, rear, and left perspective view thereof.

FIG. 9 is a partial and enlarged top, front and left perspective view of FIG. 2 taken along line 9—9, shown separately for completeness of illustration.

FIG. 10 is a partial and enlarged top, rear and left perspective view of FIG. 2 taken along line 9—9, shown separately for completeness of illustration.

FIG. 11 is an enlarged cross sectional view of FIG. 2 taken along line 11—11 between line 9—9; and,

FIG. 12 is an enlarged cross sectional view of FIG. 2 taken along line 12—12.
